CLAIM

The ornamental design for a display with a camera, microphones and speakers for telephone, as shown.

DESCRIPTION

FIG. 1 is a front, top and right side perspective view of a display with a camera, microphones and speakers for telephone, showing our new design;

FIG. 2 is a rear, top and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof, the left side elevational view is omitted as that is symmetrical to the right side elevational view thereof;

FIG. 8 is an enlarged cross-sectional view thereof, taken along line 8—8 of FIG. 3, with the internal system omitted; and,

FIG. 9 is an enlarged cross-sectional view thereof, taken along line 9—9 of FIG. 7, with the internal system omitted.
